cago, Ill., a corporation of Illinois

Application July 1, 1936, Serial No. 88,340

12 Claims. (Cl. 116—124.4)

This invention is concerned with a tuning dial of the screen type onto which may be projected the image of a selected scale. Such a dial is peculiarly suited for radio receiving sets. The means for operating the present dial is interconnected also with an associated tuning condenser, so as to assure coordinated action therebetween.

Our invention is concerned with numerous other features of importance applicable to the tuning dial of a radio receiving set where special conditions obtain. Provision is made, for example, for the transmission of light rays from an illuminant through a light box of sufficient length to prevent distortion of the image which is projected upon the screen and to accomplish this within a minimum of space and without interference with other operating units in the apparatus. Also as part of this invention we have provided means for operating a slide without lost motion or back lash, whereby the slide may be kept accurately in step with the tuning condenser whose action is coordinated therewith. Provision is also made for mounting of the tuning dial, together with its operating mechanism, as a separate unit, and for access to and adjustment or removal of individual parts thereof for purposes of repair or otherwise. In addition, the slide employed in the light projection system is of a character which may be readily changed or replaced, whereby to fit in with the operating mechanism with which it is associated.

With all such objects and purposes our present invention is concerned, as well as with numerous other features of advantage, all as will hereinafter appear. Certain suggestive embodiments of our invention are illustrated in the accompanying drawings, wherein,

Fig. 1 is a front elevation of the tuning dial unit in its entirety;

Fig. 2 is a top plan view thereof;

Fig. 3 is a vertical section taken through the light box on line 3—3 of Fig. 2;

Fig. 4 is a vertical section through the light box taken on line 4—4 of Fig. 2;

Fig. 5 is a rear elevation of the light box, together with the supports therefor;

Fig. 6 is a perspective view of the forward supporting bracket plate for the light box;

Fig. 7 is a vertical section taken on line 7—7 of Fig. 2;

Figs. 8 and 9 are details in section taken on lines 8—8 and 9—9, respectively, of Fig. 1;

Fig. 10 is a detail in vertical section through

the bearing wherein the slide shaft is rotatably supported;

Fig. 11 is a view in perspective of the mounting for the projection lens which is arranged between the slide and screen;

Fig. 12 is a fragmentary view of the film which is comprised in the slide;

Fig. 13 is a detail in section on line 13 of Fig. 3;

Fig. 14 is a perspective view of the mirror-supporting bracket;

Fig. 15 is a disassembled group view of the parts comprising the mounting for the illuminant;

Fig. 16 is a vertical section through a tuning dial projection apparatus of modified construction;

Fig. 17 is a detail of a detent which may be employed for releasably locking the slide shaft in a selected position of longitudinal adjustment, the view being a section taken on line 17 of Fig. 16; and

Fig. 18 is a detail in section taken on line 18 of Fig. 15.

The parts which are special to this invention may be mounted upon a chassis having a base A. As shown, they are assembled into a separate unit capable of being installed or removed independently of the remaining apparatus with which it is used. In this connection use is made of a frame B in which is mounted a screen C desirably of ground glass, on which is projected an image in the manner to be presently described.

Affixed upon the rear side of the frame at each of its ends are pins 20 which enter slots 21 in an elongated plate 22 from which extends laterally a lug 23 (see Figure 1). A coil spring 24 connects each lug with a hook 25 adjacent the upper end of the frame whereby to draw the plate to an upper position. A pointer 26 extends laterally from the plate into the field of the screen so as to cast a shadow thereon when there is illumination thereof. Connected with the lug 23

is a flexible cord or wire 27 extending downwardly to a tone-control shaft *a* having an operating knob (not shown), the position of the pointer being shifted with each actuation of the shaft to afford a visual indication of the tone-control adjustment at all times. A similar pointer mechanism is provided on the opposite end of the frame, operable by a cord or flexible wire 28 from a volume control shaft *d* having a suitable operating knob (not shown). Connected with this latter shaft is the usual on and off switch (not shown).

50

55

Extending rearwardly from the frame and connected thereto is a light box D whose opposite side walls 30 converge toward the rear end (see Figs. 2, 3 and 4), where one side wall of the light box is cut away and the upper and lower walls 31 thereof are extended laterally to join with an outer side wall 32 extending forwardly at an angle from the rear end of the box. By this construction we provide at the juncture of this outer side wall with the upper and lower walls, a relatively small opening at one side of the light box. The rear end of the light box may conveniently be supported as by a vertically extending main bracket E (see Fig. 5), whose lower end is affixed 15 to the chassis base. This bracket, which may serve also as a rear wall for the light box, is provided with a forward extension 36, which supports a sub-bracket F having a vertical wall 37 from whose upper end is extended forwardly a 20 horizontal wall 38. Upon the forward side of the main bracket we affix a clip G, held in place as with a screw 41. As shown in Figs. 2, 3 and 14, the clip comprises a body portion 42 through which the screw is entered, and offset legs 43, 44 and 45 25 which are spot welded to a plate 46. Bent fingers 47 formed at the edges of this plate cooperate with fingers 48 on the legs 44 and 45 in hooking over the edges of an obliquely disposed mirror 49 which may be slightly adjusted by screws 51 30 which engage the bifurcated ends of tongues 78 and 79 extending angularly from the plate 46 at points which with the screw form a triangle. A bowed spring 89 is held in position within the plate and bears against the mirror to prevent 35 vibration thereof. By the means described, a three-point mounting for the mirror is provided, and adjustments thereof may be made from the outside of the light box by manipulation of the protruding ends of the screws. In addition, the 40 lower wall of the light box may be formed with an opening 50 adjacent the mirror, permitting, if desired, application therethrough of a cloth or other implement for cleaning and polishing the mirror. The light box is supported at its front 45 end by the frame B which in turn is secured to a further bracket H (see Fig. 6) connected to a mounting plate I, which is afforded a cushioned support by the chassis base.

The forwardly extending wall 38 of the sub-bracket is apertured to mount near its front end a depending sleeve 51 provided near its upper end with a pair of spaced bosses 52 adapted to engage opposite faces of the wall whereby to secure the sleeve in place. Within the sleeve is located a 55 threaded bushing 53 provided at its lower end with a peripheral flange 54 which furnishes a bearing for the lower end of a coil spring 55, the upper end of which bears against a cap 56 having a depending flange in which is formed a plurality 60 of bayonet slots 57 which are adapted to engage a plurality of tongues 58 struck outwardly from the upper margin of the sleeve.

Upon the upper end of the bushing 53 is threaded an adjusting nut 59 which bears against the cap 56 and serves to vertically adjust the bushing against the tension of the coil spring 55. To the bushing is fixedly secured a socket sleeve 60 having a bayonet slot 75 which is adapted to coact with a stud 76 extending laterally from the neck 70 of an electric lamp J forming the illuminant for the present projecting system. Formed longitudinally upon the exterior surface of the bushing 53 is a keyway 69 adapted to receive a spline 98 extending inwardly from the cap 56 whereby the 75 rotative portion of the socket 60 is fixed. Verti-

cal adjustments may be performed with the nut 59 without disturbing the rotative portion of the mounting for the illuminant. This is important because the filament of the light bulb which lies in a plane parallel with the bulb axis should desirably remain always in line with the lens system. By the means just described this result is attained. As clearly shown in Fig. 3, the position of this illuminant is opposite the mirror and well toward the front of the light box but exteriorly 10 upon one side thereof. By means of the adjustment provided, the filament of the lamp may be located at the proper level to project the light rays axially through certain lenses presently to be described. 15

Adjacent the illuminant is an objective lens K mounted in a ring 61 which is supported upon an arm 62 depending from a plate 63 which underlies the horizontal extension wall 38 to which it is adjustably connected as by a screw 64. Pins 65 secured in the plate are adapted to slide within a slot 66 in the plate 38 whereby to assure of adjusting movements in a straight line extending between the illuminant and the mirror. Proximate to the objective lens and supported adjustably upon the ring 61 is a cap 67 having an aperture 68 for confining the emission of light rays to a limited area. A second ring 70, carried by the wall 37, is formed with a cam slot 71 for receiving an adjusting pin 72 extended radially 30 from a tube 73 having certain lengthwise slits 74 defining between them spring sections which are urged outwardly to a tight fit within the ring. At the forward end of the tube is mounted a projection lens L. By rotating the adjusting pin 35 within the cam slot the tube is shifted axially whereby to vary the position of the projection lens. The light rays passing through the objective lens are accordingly confined by its apertured cap to substantially the area of the projection lens from whence they strike the mirror for reflection back to the screen. 40

Positioned adjacent the illuminant is a slide M. It may be straight, arcuate, or circular. As here shown, it is of the circular type comprising 45 a cylindrical cup 80 of transparent material, such as celluloid, with an apertured bottom wall 81 having arcuate slots 82 at diametrically opposite points through each of which is extended a screw 83 for threaded connection with a bridge plate 84 50 on which the cup is thereby mounted for rotative adjustment. The circular walls of the cylinder are slightly inset to provide upper and lower shoulders 85 which define between them a recessed area over which may be affixed a film 86. 55 In the ends of the film are punched holes 87 (see Fig. 7) to receive tines 88 which are extended from a clip 89 by which the film ends are secured together.

The bridge plate is carried fast upon the upper 60 end of a spindle N surrounded by a hub 91 having an elongated slot 92 into which extends a stud 93 projecting radially from the spindle, there being a leaf spring 94 between the stud and one slot edge of the hub (see Fig. 10). The 65 hub is rotatably mounted in a bearing 95 having at its upper end a head 96 which is carried upon a shelf 97 extending laterally from the upper end of the forward bracket H. An upturned lip 99 on the shelf connects as at 100 with a lower extension 101 of the sub-bracket wall 37 so as to be supported in part thereby. 70

The hub which extends through the bearing is equipped at its upper end with a grooved disk 105 forming a pulley around which may be coiled one 75

or more times an endless flexible cord or wire 106. Surrounding the spindle is a coiled spring 90 confined between the disk 105 and the bridge plate 84 to which its opposite ends are respectively secured whereby to exert both compressive and torsional forces which are transmitted to the slide in all its positions of adjustment. The action of this spring supplements that of the spring 94 to prevent back lash or lost motion in the operative connections to the slide. The cord 106 is trained over an adjacent pulley 107 carried on one end of a swinging arm 108 having a pivotal mounting at 109, there being a spring 110 connecting the opposite arm end with a lug 111 which extends laterally from the bracket H. Continuing, the cord passes over a pulley 112 carried fast on a shaft 113 in operative connection with a series of plates forming part of a tuning mechanism O. This shaft, which extends horizontally below the light box, carries a second pulley 114. The belt 106 may pass over a further guiding idler 115 before returning to the pulley 105. Trained over the pulley 114 is a second belt 120 engaged by a tensioning idler 121 and passing around a driving pulley 122 which is carried fast on the tuning control shaft c. By rotation of an operating knob (not shown) affixed to the shaft c the belt is actuated to rotate the shaft 113, which through the medium of the belt 106 imparts rotation to the spindle whereon is carried the rotatable slide.

Near the lower end of the spindle is an annular groove 125 with which engages a yoke 126 pivotally supported at 127 near one end of a rocking arm 128 having an adjustable pivotal mounting 129 (see Fig. 1). Near the opposite arm end which lies adjacent the bracket H is a detent which may comprise a ball 130 confined in part within a socket therein, the projecting surface of the ball lying opposite a series of openings 131 in the bracket in any one of which the ball may partly enter. The arm 128 may accordingly be rocked about its pivot 129 to raise or lower the yoke, and with it the spindle and cylindrical slide.

As shown, the bracket is provided with three slots 131, thus providing a corresponding number of positions in which the rockable arm may be releasably secured. From the arm end opposite that whereon the yoke is attached depends a link 135 connected thereto at 136, this link having a pivotal connection 137 with a crank 138 that is mounted fast upon a shaft b having connection, if desired, with gang switches in accordance with usual practice. By rotation of this shaft, as through the medium of an operating knob (not shown), the rocking arm is actuated to shift the cylindrical slide axially to any of three positions in each of which it is releasably locked by the detent mechanism.

With a light projecting apparatus, as herein shown, it is possible to utilize any selected film with the slide. The film may be removed and a new one substituted if this be desired. Each film is desirably provided with three scales of indications (see Fig. 12) arranged circumferentially of the cylinder. The positions of these scales are such that but one of them will lie in the path of the confined light rays emanating from the illuminant for the projection of images upon the screen. The detent mechanism is so arranged that any selected scale may be positioned in the path of the light rays, and further adjustment to assure exact framing is provided by the pivot bolt 129, which, as best shown in Fig. 9, is extended through a vertical slot 140 in the bracket H, and then through a disk 141 having a hub 142 which

fits within an opening in the rocking arm 128, there being a washer 143 at the end of the hub against which pressure is exerted by a nut 144 which is screw threaded upon the bolt. By some such pivotal connection as this, the rocking point of the arm may be vertically adjusted whenever required for correct framing of the film scales upon the screen. In practice, the scales will desirably display indications applying to high wave, low wave and medium wave reception.

If desired, a multi-color screen may be interposed in the light rays, preferably at a point between the slide and projection lens. As indicated in Figs. 3 and 13, such a screen may employ a quadrant frame 33 disposed in a vertical plane 15 and pivoted as at 34 to a post 35 which is extended laterally from the sub-bracket wall 37. A lug 39 extended horizontally from the frame at a point removed from its pivotal mounting, engages the slide bottom against which it is constantly held by the tension of a spring 40 coiled around the post with one end secured to the frame, and the other to the wall 37. As the slide is shifted vertically into one of its three positions the screen frame is rocked in consequence so as to present in the path of light beams one of three openings x, y and z in the frame. In each of these openings, if desired, is mounted a transparency of individual color so as to produce upon the screen a separate color for each of the image scales that is projected from the slide. This change in color which takes place automatically with each vertical shift in the position of the slide, continues for all images that are projected from a selected object area of the slide. Accordingly, we have provided for a changeable dial a changeable color system which produces a distinctive color for each scale of the dial that is exhibited.

It is important that there be no lost motion in the transmission between the operating shaft and the cylindrical slide, so that the position of the objects projected therefrom upon the screen will always be coordinated with that of the tuning mechanism. An initial adjustment of the cylindrical slide may be made by loosening the screws 83 which connect the cup bottom 81 to the bridge plate, and then shifting the one rotatably with respect to the other to the desired position, after which the screws are again tightened. The driving force applied by the belt 106 to the pulley 105 is transmitted without loss of motion through the hub with associated leaf spring 94 to the stud 93 which extends laterally from the spindle. The belt, which may be coiled around the pulley one or more times to obviate any possibility of slippage thereupon, is further acted upon as by means of the idler pulley 107 carried upon the rocking arm urged by the spring 110 to maintain the belt taut at all times.

One advantage inherent in the use of a tuning dial of the light projecting type is that the slide may carry an extensive amount of indicia of which any selected part may be projected for magnified display over the entire surface of a relatively small screen. It is accordingly possible to display data and words considerable in amount, and by rotating the slide to bring into view an entire new display of data and words legibly exhibited upon the screen.

The mechanism thus far described involves a light projecting system in which is incorporated a mirror whereby to obtain greater distance between the illuminant and the screen. It is possible to utilize a light projecting apparatus in

which there is direct illumination, such an apparatus being suggested in Fig. 16. We have here shown a light box D whose front end is affixed to and carried by a supporting bracket 145 on which 5 is also supported the screen C. The four sides of this box converge to form a truncated pyramid having an open rear end adjacent a projection lens L supported in a tube 147 which is adjustably fitted within a sleeve 128 having a mounting 10 in a wall 149 forming part of a main bracket P, in which is also comprised a horizontal wall 150 and a rearward depending wall 151. Mounted on the bracket is a sub-bracket Q slidably secured as by a screw 152 which connects with the horizontal wall of the main bracket, the screw being positioned in a slot 153 in the sub-bracket which permits the latter to be shifted forwardly or rearwardly as required.

From the depending wall 131 is supported a ring 20 155 wherein is mounted an objective lens K in proximity to an illuminant J in the form of a light bulb which depends from a socket 158 having a mounting in the sub-bracket. Both the illuminant and objective lens are positioned within 25 in a cylindrical slide M which may comprise a film 160 surrounding the circular wall 161 of a transparent cup 162 whose bottom is adjustably secured to a bridge plate 163 affixed to the upper end of a spindle N. Below the bridge plate is a 30 chambered ring 165 from which depends a tail 166 which lies within the slot of a lug 167 extending laterally from a block 168 having a fixed mounting to support a bearing 169 into which the spindle is rotatably fitted. Formed in this 35 spindle is a longitudinal slot 170 into which is fitted a key (not shown) extending inwardly from a beveled gear 171 which is slidably fitted upon the spindle. A second beveled gear 172 in mesh with the first is affixed to one end of a tuning control shaft 173 on whose opposite end is a pulley 174 over which is trained a belt 175 which passes over a second pulley 176 on one end of a shaft c. By the connections described, the shaft c may be actuated to rotate the cylindrical slide whereby to cause projection therefrom of an image upon the screen whereby it is magnified for legible display.

The ring 165, as shown in Fig. 18, accommodates a coiled spring 180 having one end 181 anchored to the spindle, its opposite end 182 being connected to the ring adjacent its tail 166. There is thus maintained a constant one-way rotational force upon the spindle, which obviates any lost motion which might otherwise occur 55 during periods of operation.

The cylindrical slide together with the spindle on which it is mounted is adapted for axial adjustment, three positions being indicated. To accomplish this we have formed in the spindle 60 adjacent its lower end an annular groove 185 wherein is received a pin 186 which is extended from one end of a rocking arm 187 having a pivotal mounting at 188 (see Fig. 17). This arm constitutes a lateral turned end of a bar 190 65 on whose opposite end is a second arm 191 parallel with the first and pivoted at 192. A link connection 193 extends from this last arm to a crank (not shown) extending from a gang switch shaft b, this part of the construction being the 70 same as that illustrated in Fig. 1. By movements imparted to this link the bar will also be actuated whereby the pin 186 will cause the spindle to move up or down. The end of the arm 187 (see Fig. 17) may be tapered off to provide a finger 75 195 adapted to engage successively with three

notches 196 formed in a swinging arm 197 pivotally mounted at 198 and held by a spring 199 at its opposite end in constant engagement with the finger. This mechanism constitutes a simple form of detent which will sustain the spindle and cylindrical slide in any of the three adjusted axial positions that are provided.

The mechanism of Figs. 16, 17 and 18 is in general the same in operation as that already described in the remaining figures of the drawings. 10 There is this primary difference, however, and that is the light projecting apparatus operates directly instead of indirectly with the aid of a mirror. Other points of distinction are of less importance. It may be that more space will be 15 required for the installation of this direct type of projection apparatus in order to provide between the illuminant and screen sufficient distance to obviate distortion of the projected images. We would have it understood, therefore, 20 that either type may be employed, depending upon the particular conditions of use.

One important feature of our invention resides in utilization of a light projection system which comprises a box from which outside light is excluded. The small aperture adjacent the mirror or illuminant permits the latter to be located outside of the box, yet it concentrates its light rays passing through the objective lens to an area no larger than the light box aperture through 30 which these rays pass to reach the screen.

The slide is, furthermore, positioned exteriorly of the box and by reason of its cup-like form may surround the illuminant and yet remain cool because of its open top and the ventilating openings 35 through its bottom. These features of advantage, plus the provision made for moving the slide selectively through either of two paths whereby different object areas may be interposed in the light rays to throw upon the screen images 40 from different scales of a dial, render the entire apparatus particularly suitable for use with the tuning mechanism of a radio receiving set. The movements of the dial are carefully coordinated with those of the tuning mechanism, through 45 connections which may be adjusted and which function without any loss of motion. All such improvements contribute to the satisfactory operation of a tuning mechanism incorporating the principles of invention as hereinbefore described 50 and particularly pointed out in the appended claims, as follows:

We claim:

1. In a radio receiving set, the combination with a tuning mechanism, of a light projection system comprising an illuminant, a movable slide and a screen all aligned in the order named, and a rotatable connection between the tuning mechanism and slide in which the slide is also longitudinally movable, and said connection including a 60 tension device to prevent lost lateral motion and preserve coordination in the movements of the tuning mechanism and slide.
2. In a radio receiving set, the combination with a tuning mechanism, of a light projection system comprising an illuminant, a screen and a circular slide between the illuminant and screen, the slide having circumferentially extending multiple object areas, means for rotatably supporting the slide for operation with the tuning mechanism, means for adjusting the slide axially in said 70 rotatable support to definite positions whereby to project upon the screen objects from only a selected area of the slide, and a tension device connected to said slide and rotatable supporting 75

means and preventing lost lateral motion there-between in preserving coordination in the movements of the tuning mechanism and slide, and means for operating the tuning mechanism and for rotating the slide to cause projection upon the screen of only such objects as are located in the selected area of the slide.

3. In a radio receiving set, a tuning mechanism comprising a light projection system in which is an illuminant, a slide, a screen onto which images may be projected from the slide, means for moving the slide selectively through either of two paths whereby to cause projection upon the screen of objects from only a selected area 10 of the slide, a color screen movably mounted in the path of light projection, and means connecting the screen with the slide for movement therewith through one path of movement of the latter, said means cooperating with means on 15 the slide to hold said color screen stationary while said slide is being moved through its other path of movement.

4. In a radio receiving set, a tuning mechanism comprising a light projection system in which is an illuminant, a cylindrical slide mounted 20 for rotary and reciprocatory movements, a multi-color screen, a screen onto which images may be projected from the slide, means mounting the color screen for movement through a vertical plane adjacent the periphery of said cylindrical slide, and means forming an operating connection between said slide and color screen when said slide is reciprocated and a holding means for said color screen when said slide is 25 rotated.

5. In a radio receiving set, a tuning mechanism comprising a light projection system in which is an illuminant, a slide mounted for movement in two directions relative to its mounting, a color screen, an image screen onto which images may be projected from the slide through 30 said color screen, and means holding the slide and color screen in frictional engagement for concurrent movement in but one of the directions 40 of movement of said slide.

6. In a radio receiving set, a changeable station indicating mechanism in which is comprised a screen and a cylindrical longitudinally shiftable indicating scale, a multi-color screen pivotally mounted adjacent the periphery of said cylindrical scale, said screen having an offset arm adapted to extend into the longitudinally shiftable path of movement of said scale, means holding 45 said arm and scale in frictional engagement, and means for rotating and longitudinally shifting said scale to position a selected portion thereof in a distinctive color upon the screen of the station indicating mechanism.

7. In a radio receiving set, the combination 50 with a tuning mechanism of a light projection system comprising an illuminant, a slide and a screen in operative relation, means for shifting the slide through either of two movement paths, and operative connections between the 55 tuning mechanism and slide for shifting the slide through one of its movement paths, said connection including tension means to prevent lateral lost motion of the slide relative to the connections when traversing either of its movement paths whereby to preserve co-ordination in 60

the movements of the tuning mechanism and slide.

8. In a radio receiving set, a light projection system in which is a light box, a screen and a mirror mounted in spaced relation in the light box, an illuminant and a station indicator slide mounted for vertical and horizontal movements exteriorly of the light box, and means exteriorly of the box in connection with the mirror for adjusting its angular position within the box with 10 relation to a selected portion of said slide and screen in both vertical and horizontal directions.

9. In a radio receiving set, a light projection system comprising a screen, a mirror, an illuminant and a slide in operative relation, and a three-point adjustable mounting for the mirror. 15

10. In a radio receiving set, the combination 20 with a tuning mechanism and an image screen for the receiving set, a light box extending into the receiving set from said image screen, means fixedly supporting said light box and adjustably supporting an illuminant and lens system adjacent the inner end of said light box, a color 25 screen and a slide each having multiple projection areas supported by said means for relative movements through the focal path of said lens system, means for relatively positioning the lens system, slide and image screen to project upon 30 the latter through different areas of the color screen objects from different areas of the slide, means for advancing the slide through a fixed path of movement such as to project through a single area of the color screen only objects from 35 a selected area of the slide, and operative connections between said means and said tuning mechanism.

11. In a radio receiving set, a tuning mechanism comprising a light projecting system in 40 which is a light box, an image screen at one end of the box, a color screen at the opposite end of the box, an illuminant positioned to direct rays through the color screen and box onto the image screen, a slide interposed in the light 45 rays between the illuminant and color screen, and means for producing relative movement between the illuminant, color screen and slide through either of two selected paths whereby to cause projection of selected areas of the slide 50 through different areas of the color screen thence through the light box and upon the image screen.

12. In a radio receiving set, the combination 55 with a tuning mechanism of a light projecting system comprising a light box, a screen at one end of the light box, a support extending rearwardly from said light box, an illuminant and lens system suspended from said support and positioned to direct concentrated rays through the light box onto the screen, a slide also mounted on said support to extend into the light rays of said light projecting system, and means providing a pivotal mounting on said bracket and operatively connected to said tuning mechanism for producing relative vertical and horizontal movements of said slide and light projecting system.

ALBERT S. WELLS.

JESSE H. CLARK.
